HIGH-SPEED CIRCUIT BREAKER RECLOSING MECHANISM

Joseph W. Ow, Wilkinsburg, Pa., assignor to Westinghouse Electric & Manufacturing Company, East Pittsburgh, Pa., a corporation of Pennsylvania

Application November 20, 1936, Serial No. 111,822

40 Claims. (Cl. 175—294)

My invention relates to circuit breaker operating mechanisms and more particularly to high-speed reclosing mechanism for circuit breakers used to control high voltage networks or power transmission systems, and has for an object the provision of an improved high-speed reclosing mechanism that is simple, efficient and very rapid in operation, and which is automatically operable to initiate reclosing of the circuit breaker at an intermediate point in the opening stroke or at least by the time the breaker reaches full open position.

The circuit breakers or switches designed for such use are usually of relatively large size and considerable energy is necessary to close the breaker or switch; particularly in the cases where the circuit breakers are actuated to open position by strong opening forces or accelerating springs.

It is extremely important that the circuit breakers, which have opened in response to predetermined transient overload conditions, be closed as rapidly as is possible in order to prevent unduly long interruptions to the service or loss of synchronism of the apparatus in the system or network.

Heretofore it has been the general practice to use a solenoid or motor device for closing circuit breakers in such installations. This method while satisfactory in some respects has the distinct disadvantage that a relatively large amount of power is required in order to attain a rapid movement of the breaker to closed position, particularly when a large circuit breaker is involved. The large amount of power required necessitates extremely large currents with obvious resulting disadvantages. It has also been proposed to store energy in a device over an extended period of time by means of a low input motor and to utilize the energy so stored to control the breaker. The mechanisms for carrying out this, the last-mentioned method, have been objectionable for several reasons. One reason was that the mechanisms involved occupied considerable space and were not entirely satisfactory in operation, another important reason being that the prior mechanisms were not capable of producing the very high speed opening and reclosing of the breaker which is now desired.

In order to obtain the desired high speed reclosing cycle, it is necessary to provide a circuit breaker operating means that is operable to initiate reclosing movement of the breaker immediately after the circuit is interrupted without allowing the breaker to move on to its full

open position. As was previously pointed out in the copending application of J. B. MacNeill and A. W. Hill, Serial No. 700,276, filed November 29, 1933, now Patent No. 2,125,835, assigned to 5 the assignee of this invention, it has been found that in many modern circuit breakers, complete circuit interruption is accomplished when the moving contact member has travelled only a relatively small fraction of its full opening movement. Thus, in a particular instance, when the travel of the movable contact member is 44 inches, it has been found that complete circuit interruption is attained when the movable contact member has travelled only 10 inches 15 toward full open position. However, it is desirable to use a certain safety factor and therefore it has been found desirable to permit the movable contact member to travel a slightly greater distance, for example, 12 to 14 inches to insure interruption of the circuit before initiating reclosing.

It is important, however, that the breaker be trip free of the closing means, i. e., capable of 20 being opened irrespective of the closing movement or position of the closing means; otherwise serious damage may be caused to apparatus in the system if the breaker is closed when a fault or other predetermined condition still exists in the system.

It is accordingly an object of my invention to 25 provide an improved high speed reclosing mechanism for a circuit breaker.

Another object of my invention is the provision 30 of an improved form of operating means for a circuit breaker for effecting high speed opening and closing of the breaker.

Another object of my invention is to provide 35 an improved form of circuit breaker operating means that is capable of delivering a large amount of power in a short period of time to effect a very high speed closing of the circuit breaker and in which the breaker is trip free of the closing means.

Another object of my invention is the provision 40 of operating mechanism for a circuit breaker which occupies a relatively small amount of space and which is simple, reliable in operation, and relatively inexpensive to manufacture.

Another object of my invention is to provide an 45 improved operating mechanism for a circuit breaker characterized by the use of one or more spiral power springs, in which energy is stored and releasably held, for closing the breaker.

Another object of my invention is the provision 50 of an improved operating mechanism for a

circuit breaker embodying an energy storing device for closing the breaker in which the energy is automatically restored after each closure of the breaker.

Another object of my invention is the provision of operating means for a circuit breaker comprising an energy storing device for closing the breaker and trip free thrust transmitting means for transmitting the energy stored in said device to the circuit breaker.

Another object of my invention is the provision of an improved operating mechanism for a circuit breaker embodying one, or more, spiral power springs for closing the breaker, and a trip-free clutch mechanism for effecting a driving connection between the springs and the breaker operating member.

Another object of my invention is to provide an improved operating mechanism for a circuit breaker embodying an energy storing device in the form of a spiral power spring which is releasable to close the breaker, in which a band friction clutch and an electromagnetic clutch are interposed in series between the power spring and the breaker for effecting a driving connection therebetween.

Another object of the invention is the provision of a circuit breaker operating means that is operable at a predetermined point in the opening movement of the breaker immediately after the circuit is interrupted to initiate reclosing of the breaker before the breaker reaches full open position.

Another object of the invention is the provision of a circuit breaker operating means embodying a closing means that is automatically operable to initiate reclosing of the breaker as soon as the circuit is interrupted and before the breaker reaches full open position, and in which the breaker is trip free of the closing means. These last two objects are carried out in the specific embodiment of the invention shown and described by a closing device comprising a power spring in which energy is stored and releasably held. The spring is automatically released and clutched to the breaker at a point in the opening movement immediately after the circuit is interrupted and before the full open position of the breaker has been reached. This effects the desired high speed reclosing cycle. The breaker is trip free of the closing spring by reason of the fact that the electromagnet clutch can be released by a trip means so that the breaker is disconnected from the closing spring.

Another object of my invention is the provision of an improved operating mechanism for a circuit breaker embodying an energy storing device for closing the breaker in which a novel form of releasable holding means is provided for holding the breaker in closed circuit position together with an electro-responsive trip device for releasing said holding means.

The problem of providing a fast reclosing cycle for a circuit breaker has proved difficult of a satisfactory solution. One form of apparatus for accomplishing a fast reclosing cycle has been described and claimed in the copending application of John B. MacNeill and Alan W. Hill, Serial No. 700,276, filed on November 29, 1933 now Patent No. 2,125,835, assigned to the assignee of the present invention. In the apparatus of the above-mentioned copending application, however, the circuit breaker is not trip free of the closing means. The present invention provides an improved circuit breaker operating means for accomplishing

the desired fast reclosing cycle and novelly incorporates a feature that makes the breaker trip free of the closing means.

The novel features that are considered characteristic of my invention are set forth in particular in the appended claims; the invention itself, however, both as to structure and operation, together with additional objects and advantages thereof, will best be understood from the following detailed description of a specific embodiment when read in connection with the accompanying drawings, in which:

Figure 1 is a front view, partly in elevation and partly in section, of the operating mechanism embodying the features of my invention;

Fig. 2 is a vertical sectional view of the mechanism illustrated in Fig. 1 taken on the line II--II thereof, looking in the direction of the arrows;

Fig. 3 is a vertical sectional view of the operating mechanism illustrated in Fig. 1 taken on the line III--III thereof, looking in the direction of the arrows;

Fig. 4 is a fragmentary view showing a portion of the mechanism, together with one of the control switches;

Fig. 5 is a wiring diagram illustrating one manner of connecting apparatus in a control circuit; and

Fig. 6 is a fragmentary view, on a reduced scale, of the right hand end of the apparatus shown in Fig. 1.

The operating mechanism comprises, in general, a base 7, a frame comprising a pair of supports 9, an energy storing device indicated generally at 11 for closing the circuit breaker, a band friction electromagnetically controlled clutch indicated generally at 13 for transmitting the energy when released to the breaker operating member, a band friction light load latch indicated generally at 15 for holding the circuit breaker in closed position, a motor 17 for storing energy in the energy storing device, an electromagnetic power latch indicated generally at 19 for holding the energy stored in said device, and a plurality of control circuits for controlling the various elements.

The entire operating mechanism for the circuit breaker is supported by the base 7 which may be of any suitable material, preferably metal. A pair of vertical supports 9 are secured to the base 7 by means of threaded bolts 21, which are adapted to pass through flange portions 23 of the supports 9 and engage in threaded openings provided in the base 7. If desired, the vertical supports 9 may be secured to the base 7 by various other means, as for example by welding or they may be formed integral with the base. Each of the supports 9 is divided into two sections, as shown in Fig. 6, each section being provided with a semi-circular bearing 25 for receiving a shaft 27. The shaft 27 is adapted to be rotatably mounted in the bearing portions 25. The sections are held together by means of threaded bolts 29 which pass through extensions 31 provided on each section, the lower extensions 31 being provided with threaded openings to receive threaded portions of the bolts 29. A means is provided for adjusting the position of the shaft 27 and for holding the same against rotation in its adjusted position. This means, best shown in Fig. 6, comprises a lever arm 33 having a square opening in the rounded end thereof for receiving a squared portion 32 at the free end of the shaft 27. The end of the lever arm 33 extends to a position between two adjust-

ing bolts 34 carried by lugs 36 formed integral with the support 9. Lock nuts 38 are provided for locking the adjusting bolts in adjusted position. The adjusting bolts 34 and the lever arm 30 provide a means for introducing any desired initial tension in the springs 33 to be herein-after described and also function to hold the shaft 27 in fixed adjusted position against rotation.

The energy storing device for supplying the power required for closing the circuit breaker and the means for storing energy therein are similar in some respects to the energy storing device and the means for storing energy therein disclosed and claimed in the copending application of Joseph W. Ow and E. K. Read, Serial 109,702, filed on November 7, 1936, assigned to the assignee of this invention, and which is now Patent No. 2,140,371 granted December 13, 1938.

The energy storing device comprises one or more spiral power springs 33. The inner ends of the springs are secured to a flattened portion of the shaft 27 by means of bolts 35. The outer ends of the spiral springs are secured to a U-shaped bail 37 by means of bolts 39. The legs 25 of the U-shaped bail are provided with openings for rotatably mounting the same upon cylindrical portions 41 of the fixed shaft 27.

A power latch indicated generally at 19 is provided for holding the spring bail 37 in position with the springs flexed with energy stored therein. The power latch illustrated comprises a support 45 secured to the base 7 by means of bolts 47, a U-shaped bracket 49 (Fig. 3) for pivotally supporting a latch member 51, a spring 53 connected in tension between one end of the latch 51 and a lug 55 on the base 45, and an electromagnet 57 cooperating with an armature 59 carried by the nose of the latch 51. A lug 61 is secured to the bail by any suitable means, as by welding, and is adapted to be engaged by the latch 51 to hold the bail 37 in energy stored position with the power springs 33 flexed. The electromagnet 57 is adapted to be energized to attract the armature 59 to cause the latch 51 to move about its pivot to release the lug 61 and the spring bail 37.

The means for flexing the spring 33 for storing energy therein comprises a motor 17 adapted to drive a shaft 63 by means of a worm 65 and a worm gear 67. The shaft 63 has secured thereto a disc 69 provided with a lug 71 of semi-circular cross-section, as shown in Fig. 4. The lug 71 and the disc 69 constitute a crank arm for rotating the bail 37 to flex the power springs and thus store energy therein. The lug 71 is adapted to engage a lug 73 secured to the bail 37. The disc 69 when rotated in a counter-clockwise direction, as viewed in Fig. 4, causes the lug 71 to engage and drive the lug 73 to effect a partial rotation of the bail 37. When the bail has been rotated to a position 75 (see Fig. 4), the latch 51 (Fig. 3) engages the lug 61 to hold the bail in energy stored position. The normal position of the parts described above is illustrated in Fig. 4. The normal position of the lug 71 indicated at 77 is such that it just clears the lug 73, the bail being held in latched position by the latch 51. When the bail arrives at latched position, the lug 73 engages and moves a plunger 79 to open a limit switch 81 connected in the motor circuit. The slight overtravel of the motor causes the lug 71 to move to the normal position 77. Upon release of the bail 37, the spiral power springs discharge their energy and cause 75

rotation of the bail 37 to a position 83 to effect a closing operation of the circuit, as will be hereinafter described. Movement of the bail from the normal latched position effects a release of the plunger 79, thus allowing the limit switch 81 to be closed under the influence of its biasing spring 85. Closing of the limit switch 81 completes the motor circuit, thus causing the motor to rotate the shaft 63. Rotation of the shaft 63 causes the disc 69 to be driven in a counter-clockwise direction, as viewed in Fig. 4, moving the lug from the position 77 to a position 87, in which it engages the lug 73 secured to the bail 37. Continued rotation of the motor causes the lug 71 to drive the lug 73 and rotate the bail back to its normal energy stored or charged position, in which it is relatched by the latch 51. At this time the motor circuit is again opened by the limit switch 81 and the over-travel of the motor moves the lug 71 to its normal position 77. It will thus be seen that energy is automatically restored in the power springs immediately after each release of the same, and the power springs and bail are held in a normal energy stored or charged position ready to effect a subsequent closing operation of the circuit breaker.

The circuit breaker (not shown) is adapted to be operated by means of an operating member 89, which is connected to the movable contact supporting rod of the breaker by the usual bell-crank lever or by any other suitable means. The operating member 89 is pivotally connected by means of a pin 91 to a pair of circuit breaker operating levers 93. The circuit breaker operating levers 93 are secured for movement together by means of the pin 91 and the nut, bolt and spacer assembly 95. The circuit breaker operating levers 93 are connected to bearing rings 97 mounted for rotation on a pair of drums to be hereinafter described. The particular structure of the circuit breaker which the apparatus is adapted to control is not an important part of my invention. Any conventional form of circuit breaker which is biased to the open circuit position by gravity or accelerating springs or both will suffice, and since switches of this general type are old and well known in the art it is not deemed necessary to illustrate the same.

A trip-free connecting mechanism indicated generally at 13 is provided for causing driving engagement between the spring bail 37 and the breaker levers 93 to transmit the energy stored in the power springs when the bail is released to the operating member 89 for effecting a closing operation of the circuit breaker. For this connection it is desirable to provide means whereby the connection may be accomplished with a minimum expenditure of energy and at the same time to insure that a direct and positive connection will be maintained during the closing operation. It is also desirable to provide for breaking the connection between the spring bail 37 and the breaker operating levers 93 at any time while they are in driving engagement in order to prevent the contact members of the circuit breaker from completely closing when a short circuit or overload occurs on the circuit controlled by the breaker. It is also desirable that the driving connection may be effected at any time even during the movement of the circuit breaker to the open circuit position in order that the breaker may be driven back to closed position before it has completed its opening movement. The connecting means for performing these functions will now be described.

A drum 99 is rotatably mounted on cylindrical portions of the shaft 27 and is secured for rotation with the spring bail 37 by means of bolts 101. Surrounding the drum 99 is positioned a helical clutch band 103, the upper end or high torque end of which is secured to the breaker levers and to the bearings rings 97 by means of a bolt 105. The clutch band 103 is in the form of a helix wound around the drum 99 with a slight clearance therefrom so that it is capable of rotating on the drum. The low torque end 107 of the helical band is secured to a rotatable wheel 109 by any suitable means. The wheel 109 is rotatably mounted on a sleeve 111 which may be either formed integral with the drum 99 or keyed thereto by a key connection 113, as shown in Fig. 1. An electromagnetic clutch indicated generally at 115 is provided for clutching the bail 37 and drum 99 to the wheel 109. A clutch coil 117 is mounted within a housing core 119 of magnetic material. The core 119 is provided with a face 121 adapted to be clutched to a face plate 123 connected by means of a diaphragm 125 to the wheel 109. The diaphragm is connected to the wheel 109 and the clutch plate 123 by means of bolt assemblies, as shown in Fig. 1. The clutch plate 123 is rotatably mounted on the sleeve 111. It will thus be seen that the clutch plate is capable of slight longitudinal movement along the sleeve 111 and yet is secured for rotation with the wheel 109. A friction band 127 may be secured to the clutch plate 123 to insure a better frictional engagement between the surface 121 of the core 119 and the clutch plate 123. The friction band 127 may be secured to the clutch plate in any suitable manner, as, for example, by rivets, as shown in Fig. 1. The magnetic core 119 is mounted for rotation with the sleeve 111 and the drum 99 by means of a suitable key connection to said sleeve. The above described clutch mechanism is similar in some respects to the clutch mechanism described and claimed in the copending application of Paul Duffing and Walter Hergert, Serial No. 613,456, filed May 25, 1932, assigned to the assignee of this invention, and which is now Patent No. 2,068,402, issued January 19, 1937.

The clutch coil 117 is adapted to be energized simultaneously with the energization of the power latch electromagnet coil 57, as will be hereinafter described in connection with the description of the control circuits illustrated in Fig. 5.

The operation of the band friction electromagnetic clutching arrangement will now be described. When the power latch coil 57 and the clutch coil 117 are simultaneously energized, the spring bail is released by the latch 51 and is rotated in a clockwise direction, as viewed in Fig. 3, by means of the energy stored in the power springs 33. The drum 99 being secured to the bail, and the sleeve 111 and the core 119 being connected to the drum; these elements will be rotated by said springs. The coil 117 being energized attracts the clutch plate 123 and drives the same by reason of the clutching engagement of the surfaces 127 and 121. Rotation of the clutch plate 123 effects rotation of the wheel 109, the rotation of which causes the turns of the helical band to successively tighten and frictionally engage the drum 99. The high torque end of the helical band being connected to the breaker operating lever causes rotation of the same to effect a closing operation of the circuit breaker. It will be noted that only a slight force is necessary at the low torque end of the helical band to lock the same in frictional engagement with the drum 99.

After the low torque end of the band has been locked in frictional engagement with the drum 99, the remaining bands are tightened upon the drum by the rotation thereof against the biasing force of the circuit breaker. As long as the winding 117 is energized, the spring bail and drum will be clutched by the helical band 103 to the breaker operating levers 93. If, however, the winding 117 is deenergized, the wheel 109 is released and the helical band immediately releases its grip on the drum 99, thus allowing the drum 99 to continue its rotation and at the same time allowing the breaker to move under its bias to the open circuit position, during which movement the helical band is rotated in a counter-clockwise direction about the drum 99. By this structure the breaker and the breaker operating member are trip-free in any position of the drum 99, and the breaker can be tripped to open position even during a closing operation by deenergization of the coil 117.

The circuit breaker being of the type which is biased to open circuit position by gravity and accelerating springs or both, a means must be provided for releasably holding the breaker in closed circuit position. The preferred form of latch means for holding the circuit breaker operating member in a closed circuit position will now be described. A stationary drum 129 is mounted on the support 9 by any suitable means such as the bolts 130. A helical band 133 is wound about the stationary drum in an opposite sense from the winding direction of the helical band 103 and has a slight clearance from said drum so that it can rotate thereon. The high torque end of the helical band 133 is adapted to be secured to one of the breaker operating levers 93 by means of a bolt 135. The low torque end of the helical band 133 is provided with a latch shoulder 137 (Fig. 2) adapted to be engaged by a latch 139 which is pivotally mounted on the upper section of one of the vertical supports 9 by means of a bracket 141. The latch 139 is biased to latch engaging position by means of the coil spring 143 (Fig. 1) held in compression between the latch and a socket 145 provided in a projection 147 formed integral with the upper section of the vertical support 9. A shunt trip electromagnet 149 is mounted on the upper section of the vertical support 9 by means of a bracket 151. An armature 153 is pivotally mounted adjacent the electromagnet by means of a pivot pin 155 carried by a lug on the vertical support 9. A hook member 157 is carried by the end of the armature on the opposite side of the pivot pin from the electromagnet, for engaging and lifting the latch 139 when the electromagnet 149 is energized. The arrangement described above provides an efficient light load latch means for holding the breaker in closed circuit position in which the extremely heavy load of the breaker bias can be held by means of the light load latch at the low torque end of the helical band. The operation of the latch means is as follows: When the breaker is moved to closed position by means of the spring bail 37 as described in a preceding paragraph, the helical band 133 is rotated in a clockwise direction about the stationary drum 129 so as to move the latch shoulder on the band toward the position shown in Fig. 2. The latch shoulder 137 is so positioned on the low torque end of the helical band that the slight overtravel of the breaker levers past closed circuit position causes the latch shoulder 137 to move under the latch 139 so as to be engaged thereby. The

breaker bias returns the breaker levers from their overtravel position to the normal closed circuit position, and in so doing tends to tighten the band 133 on the drum 129, since the light load end of the band is held in positive latched position. It will thus be seen that the light load latch 139 provides a means for effectively holding the breaker in closed circuit position against the bias of gravity and the accelerating springs by reason of the latch 139 engaging the shoulder 137 plus the frictional engagement of the helical band 133 on the drum 129. The breaker may be tripped to open position by energizing the shunt trip electromagnet 149 which causes the armature thereof to release the latch 139 thus releasing the helical band from its engagement with the drum 129. The breaker is now free to move to open circuit position under its own bias.

The control circuit for the apparatus is illustrated diagrammatically in Fig. 5 and will now be described. The motor 17 is connected in series with the limit switch 81 across supply lines L₁, L₂. The electromagnetic shunt trip coil 149 is connected in series with a manual or relay controlled switch 159 across said supply lines. The clutch coil 117 and the power latch coil 57 are connected in parallel by a lead 161 and a common lead 163 across the supply lines L₁, L₂. A manual control or relay controlled switch 165 is interposed in series in the common lead 163. A relay switch 167 is connected in series with a second common lead 169 for the clutch coil and the power latch coil. The branch lead 171 for the clutch coil has connected in series therewith a relay switch 173 adapted to be controlled by a current-responsive overload trip coil 175. The coil 175 is adapted to be coupled to the circuit controlled by the circuit breaker and is responsive to a predetermined overload to open the branch circuit 171 of the clutch coil. If desired, the trip coil 175 may be arranged to open its contacts 173 in response to some other predetermined condition in the system or network in ways well known in the art. Relay switch 167 is controlled by a relay coil 177 connected in a circuit across the supply lines L₁, L₂. The relay coil 177 is adapted to be controlled by an interlock switch 179 associated with the breaker. The interlock switch is adapted to be closed at a predetermined point in the movement of the breaker toward open circuit position immediately after the circuit is interrupted and before the full open position is reached so as to energize the relay 167 to effect a fast reclosing operation of the circuit breaker. A selective switch 178 is interposed in the circuit of the relay 167. The switch 178 is adapted to be controlled by a relay from some remote point for selectively rendering the relay 167 operable or inoperable to effect the automatic fast reclosing cycle when the interlock switch is closed. An additional switch (not shown) may be provided in the circuit of the relay 167 for opening the same after a predetermined number of reclosing operations in any well known manner.

The operation of the control apparatus will now be briefly described. With the parts in the position shown in Figs. 1 and 5, that is, with the springs in energy stored position and the bail in latched position and with the breaker in the full open circuit position; if it is desired to close the circuit breaker, the manual or relay controlled switch 165 is closed for completing the circuit to the power latch coil 57 and the clutch coil 117.

Energization of the latch coil 57 effects a release of the spring bail by the latch 51. The spring bail is rotated in a clockwise direction by means of the energy stored in the power springs, and since the clutch coil 117 is simultaneously energized, the motion of the spring bail 37 is transmitted through the drum 99, the core 111, clutch plate 123 (the clutch being energized), and wheel 109 to the low torque end of the helical band 103. A slight rotation of the wheel 109 causes the band 103 to tighten and frictionally engage the drum 99. The movement of the bail 37 is now transmitted directly from the drum 99 through the helical band 103 to the breaker operating levers 93 causing rotation of the same to effect a closing operation of the breaker by the operating member 83. If the trip coil 175 is operated to open the contacts 173 during the rotation of the drum 99 to close the breaker, as for example in response to some predetermined condition in the system or network, the clutch coil will be immediately deenergized. Deenergization of the clutch coil 117 releases the band 103 from its engagement with the drum 99 allowing the breaker to move under its bias to open circuit position and also allowing the drum 99 to continue its rotation in a clockwise closing direction until the springs are unwound. As soon as the spring bail moves away from its normal charged position, the circuit to the motor is established by means of the closing of the limit switch 81. Thus the breaker is always trip free of the closing means, i. e., the breaker can be opened irrespective of the position or closing movement of closing means because the clutch is operable to release the breaker from the closing means. The motor drives the crank comprising the lug 11 and the disc 69 so as to restore energy in the springs 33 by rotating the bail back to its normal position as soon as the springs have completely discharged their energy. When the bail is driven back to its original or normal position, it is reengaged by the latch 51 so that the springs and bail are in position to effect a subsequent reclosing operation.

As the breaker is actuated to closed position, the helical band 133 is rotated in a clockwise direction about the stationary drum 129, and if there is no abnormal condition present in the main circuit at the time the breaker closes the main circuit, complete closing operation of the breaker will be effected. During the slight overtravel of the breaker beyond the fully closed position the latch shoulder 137 moves under the latch 139. During the return movement of the breaker from its over-travel, the helical band 133 is tightened to frictionally engage the stationary drum. The latch 139 thus effectively holds the low torque end of the helical band, so that the frictional engagement of the coils of the band about the drum effectively holds the circuit breaker in closed circuit position. Upon completion of the closing operation, the clutch coil is deenergized in any conventional manner, for example, by the opening of an auxiliary switch (not shown) arranged to open upon completion of the closing operation of the mechanism or breaker.

If it is desired to open the breaker, the manual or relay controlled switch 159 is closed to energize the shunt trip coil 149. Energization of the coil 149 causes the armature 153 to move the latch 139 to release the low torque end of the helical band 133. The release of the low torque end of the helical band causes all the turns of the

band to release their frictional grip on the drum 129 to thus free the breaker levers, so that the breaker can move to the open circuit position under its own bias. If desired, other electro-responsive trip devices may be provided for moving the latch 139 to the released position in response to different predetermined conditions. For example, the shunt trip coil 149 which releases the breaker latch 139 may be arranged to be energized to cause automatic opening of the breaker in response to some predetermined abnormal conditions in the system or network, as for example, an overload condition. This can be carried out in a number of ways well known in the art.

If quick automatic reclosing operation of the breaker is desired, the selective control switch 178 in the circuit of the relay 177 is closed. When the breaker is tripped open in response to an abnormal condition or overload in the main circuit, the relay 167 is energized at a predetermined point in the opening movement of the breaker by the closing of the interlock switch 179, namely, at some point just after the arc formed incident to opening the breaker has been extinguished, to close the relay contacts 167 for simultaneously energizing the power latch coil 57 and the clutch coil 117. Energization of the power latch coil and the clutch coil effects a release of the spring bail in its normal charged position by the latch 51 and a clutching of the drum to the wheel 109 and the low torque end of the helical band 103. The movement of the breaker lever towards open position applied to the high torque end of the band 103, and the rotation of the wheel 109 by the spring bail 31, drum 99 and coil 117 immediately causes tightening of the band 103, so that it frictionally engages the drum to halt the movement of the breaker towards open position and immediately transmits the motion of the drum 99 to said breaker lever to effect quick reclosing operation of the circuit breaker. By this arrangement it is not necessary to wait until the breaker reaches full open position before effecting a reclosing operation, and the time necessary for reclosing the breaker is thus materially reduced.

It will be apparent that many changes can be made in the structure of the control apparatus without departing from the spirit of my invention. For example, other forms of latching means may be provided for holding the breaker in closed circuit position. For example, a latch means of the same general type as the power latch may be substituted for the band friction light-load latching scheme 15 illustrated in Fig. 1. However, with such modification the wear on the latch engaging surfaces is considerable, since such surfaces are subject to a considerable load, and for this reason the band friction light-load latch device is considered the more efficient method of releasably holding the breaker in the closed circuit position if the breaker is of very large size. If desired, a drum and band friction light-load latch arrangement may be substituted in for the power latch to hold the spring bail in the normal energy stored or charged position. In such case an additional drum and helical band having a latch device for engaging and holding the light-load end of the helical band, similar to the corresponding elements for holding the breaker in closed circuit position, would be provided. Various changes could also be made in the connection of the apparatus in a control circuit. If desired, a crank means may be pro-

vided for manually operating the shaft 63 for storing energy in the power springs. This means might consist of an extension (not shown) formed integral with the shaft carrying the worm 65. The free end of the extension would be provided with a crank portion adapted to receive a hand crank, not shown. By such means the disk 69 could be operated to rotate the bail 31 to its normal energy stored or charged position. In addition to manually storing energy in the springs, the manually controlled crank could be used to slowly move the circuit breaker to various positions for adjustment or repair by releasing the power latch and then hand-cranking the motor shaft so as to move the breaker to any desired position for such purposes. The number of springs may be increased or decreased to suit the particular power requirements of the apparatus.

The motor may be of relatively small size and the arrangement of the gears such that the motor completes its energy-storing cycle in any desired period of time. The size of the motor and arrangement of the gears may be changed to meet the particular requirements or needs.

It will thus be seen that I have provided an improved high-speed reclosing mechanism in which a relatively large amount of energy may be stored for effecting the closing operation of the breaker, which requires only a small input device for storing the energy necessary for effecting such operation, the arrangement being such that the energy is automatically restored in such device immediately after the release thereof, so that the apparatus is normally held in a condition ready to effect rapid subsequent reclosing operations. The mechanism is operable to initiate reclosing operation of the breaker at an intermediate point in the opening stroke before the breaker reaches full open position and the breaker is trip-free of the closing means.

By the use of the spiral power springs and the specific arrangement for storing energy therein, I have effected considerable reduction in the space necessary for the apparatus as compared with the amount of space utilized by other forms of control apparatus of comparable power. The mechanism also includes an improved means for transmitting the energy stored in the power springs to the breaker operating member, which transmitting means is trip-free in any position of the parts, thus providing a desirable safety factor. The improved form of transmitting means also permits a driving connection to be established between the power springs and the breaker operating member during opening movement of the circuit breaker, so as to provide a fast reclosing cycle.

The present invention in certain aspects forms a further development of and improvement over the invention disclosed in my copending application for Control apparatus, Serial No. 97,936, filed August 26, 1936, assigned to the assignee of this invention, and which is now Patent No. 2,157,863 granted May 9, 1939.

While a specific form of the invention has been illustrated, it is obvious that various changes and modifications may be made without departing from the spirit of the invention, and I desire therefore, that the invention be limited only by the prior art, and the scope of the following claims.

I claim as my invention:

1. In a control apparatus for a circuit breaker, an operating member connected to the break-

er to open or close the same, an energy storing device, means for storing energy in said device, means for releasably holding the energy stored in said device, means including a clutch mechanism interposed between said device and said operating member operable to transmit the stored energy when released from said device to said operating member to close the breaker, and means for releasing said holding means and simultaneously operating said clutch mechanism to close the breaker.

2. In a control apparatus for a circuit breaker, an operating member connected to the breaker to open or close the same, spiral power spring means, means for flexing said spring means to store energy therein, means for releasably holding said spring means in flexed position, means including a clutch mechanism interposed between said spring means and said operating member operable to provide a driving connection between the spring means and the operating member, and means for releasing said spring holding means and simultaneously operating said clutch mechanism to close the breaker.

3. In a control apparatus for a circuit breaker, an operating member connected to the circuit breaker biased to an open circuit position and movable to a closed circuit position to open or close the breaker, a spiral power spring, means for flexing said spring to store energy therein, means for releasably holding said spring in flexed position, means including a trip-free clutch mechanism interposed between said spring and said operating member operable to effect a driving connection between the spring and operating member, means for releasing said spring holding means and simultaneously operating said clutch mechanism to cause said spring to move said operating member to the closed circuit position, means for releasably holding said operating member in the closed circuit position, and a trip device for releasing said last-mentioned holding means.

4. In a control apparatus for a circuit breaker, an operating member connected to the breaker to open or close the same, a power spring, means for tensioning said spring to store energy therein, means for releasably holding said spring in tensioned position means including a clutch mechanism interposed between said spring and said operating member operable to provide a driving connection therebetween, means for releasing said spring holding means and operating said clutch mechanism to cause said spring to close the breaker.

5. In a control apparatus for a circuit breaker, an operating member connected to the breaker movable to open or close the same, a power spring, means for flexing said spring to store energy therein, means for releasably holding said spring in flexed position, means including a clutch mechanism interposed between said spring and said operating member operable to effect a driving connection between the two, an electromagnet for operating said clutch mechanism, means for releasing said holding means and energizing said electromagnet to cause said spring to close the breaker.

6. In a control apparatus for a circuit breaker, an operating member connected to the breaker movable to open or close the same, a spiral power spring, means for flexing said spring to store energy therein, means for releasably holding said spring in flexed position, means including a clutch mechanism interposed between said spring and said operating member operable to

effect a driving connection between the two, an electromagnet for operating said clutch mechanism, means for releasing said holding means and energizing said electromagnet to cause said spring to close the breaker.

7. In a control apparatus for a circuit breaker, an operating member connected to the breaker movable to open or close the same, spring means, means for flexing said spring means to store energy therein, means for releasably holding said spring means in flexed position, means including a band friction clutch mechanism interposed between said spring means and said operating member operable to effect a driving connection between the two, an electromagnet for operating said clutch mechanism, means for releasing said holding means and energizing said electromagnet to cause said spring means to close the breaker.

8. In a control apparatus for a circuit breaker, an operating member connected to the breaker movable to open or close the same, a spiral power spring, means for flexing said spring to store energy therein, means for releasably holding said spring in flexed position, means including a band friction clutch mechanism interposed between said spring and said operating member operable to effect a driving connection between the two, an electromagnet for operating said clutch mechanism, means for releasing said holding means and energizing said electromagnet to cause said spring to close the breaker.

9. In a control apparatus for a circuit breaker, an operating member connected to the breaker movable to open or close the same, a spiral power spring, means for flexing said spring to store energy therein, means for releasably holding the spring in flexed position, an electromagnet for releasing said holding means, means including a clutch mechanism interposed between said spring and said operating member operable to effect a driving connection between the two, a second electromagnet for operating said clutch mechanism to effect said connection, means for simultaneously energizing said electromagnets to cause said spring to close said breaker.

10. In a control apparatus for a circuit breaker, an operating member connected to the breaker biased to an open circuit position and movable to a closed circuit position to open or close the breaker, a power spring, means for flexing said spring to store energy therein, means for releasably holding said spring in flexed position, an electromagnet for releasing said holding means, means including a clutch mechanism interposed between the spring and the operating member operable to effect a driving connection between the two, a second electromagnet for operating said clutch mechanism to effect said connection, means for simultaneously energizing said electromagnets to cause said spring to close said breaker.

11. In a control apparatus for a circuit breaker, an operating member connected to the breaker biased to an open circuit position and movable to a closed circuit position to open or close the breaker, a spiral power spring, means for flexing said spring to store energy therein, means for releasably holding said spring in flexed

position, an electromagnet for releasing said holding means, means including a trip-free clutch mechanism interposed between the spring and the operating member operable to effect a driving connection between the two, a second electromagnet for operating said clutch mechanism to effect said connection, means for simultaneously energizing said electromagnets to cause said spring to close the breaker, means for releasably holding said operating member in the closed circuit position, and a trip device responsive to predetermined conditions for releasing said last-mentioned holding means.

12. In a control apparatus for a circuit breaker, an operating member connected to the breaker biased to an open circuit position and movable to a closed circuit position to open or close the breaker, a spiral power spring, means for flexing said spring to store energy therein, means for releasably holding said spring in flexed position, an electromagnet for releasing said holding means, means including a trip-free band friction clutch mechanism interposed between the spring and the operating member operable to effect a driving connection between the two, a second electromagnet for operating said clutch mechanism to effect said connection, means for simultaneously energizing said electromagnets to cause said spring to close the breaker, means for releasably holding said operating member in the closed circuit position, a trip device for releasing said last-mentioned holding means, and means for deenergizing said second electromagnet to release said clutch in response to predetermined conditions.

13. In a control apparatus for a circuit breaker, an operating member connected to the breaker movable to open or close the same, a spiral power spring, means for flexing said spring to store energy therein, means for releasably holding said spring in flexed position, a band friction clutch mechanism interposed between said spring and said operating member operable to effect a driving connection between the two, said clutch mechanism comprising a drum connected to said spring, a helical band disposed around said drum having the high torque end connected to said operating member and an electromagnetic clutch disposed between the low torque end of the band and said drum for effecting a driving connection therebetween, means for releasing said spring holding means and substantially simultaneously energizing said electromagnetic clutch to cause said spring to move said operating member to close the breaker.

14. In a control apparatus for a circuit breaker, an operating member connected to the breaker biased to an open circuit position and movable to a closed circuit position to open or close the breaker, a power spring, means for flexing said spring to store energy therein, means for releasably holding said spring in flexed position, an electromagnet for releasing said holding means, means including a trip-free clutch mechanism interposed between the spring and the operating member operable to effect a driving connection between the two, a second electromagnet for operating said clutch mechanism to effect said connection, means for simultaneously energizing said electromagnets at a predetermined point in the opening movement of said breaker to cause said spring to stop the opening movement and reclose the breaker, means for deenergizing said second electromagnet in response to predetermined conditions, means for releasably holding said operating member in the

closed circuit position, and a trip device for releasing said last-mentioned holding means to allow said breaker to move to the open circuit position.

15. In a control apparatus for a circuit breaker, an operating member connected to the breaker biased to an open circuit position and movable to a closed circuit position, a power spring, an electric motor means for flexing said spring to store energy therein, a motor circuit for operating said motor, a limit switch in said circuit opened when said spring reaches said flexed position, means for releasably holding said spring in the flexed position, means including a releasable clutch mechanism interposed between said spring and said operating member operable to effect a driving connection therebetween, means for releasing said spring holding means and simultaneously operating said clutch mechanism to close the breaker, means for releasably holding said operating member in the closed circuit position, a trip device for releasing said last-mentioned holding means to allow said breaker to open, and means for releasing said clutch mechanism to disconnect said driving connection between said spring and the operating member in response to predetermined conditions.

16. In a control apparatus for a circuit breaker, an operating member connected to the breaker movable to open or close the same, a power spring, an electric motor means for flexing said spring to store energy therein, a motor circuit for operating said motor, a limit switch in said circuit adapted to be opened when said spring reaches its flexed position, means for releasably holding said spring in flexed position, means including a clutch mechanism interposed between said spring and said member operable to effect a driving connection therebetween, and means for releasing said holding means and simultaneously operating said clutch means for causing said spring to move said operating member to close the breaker.

17. In a control apparatus for a circuit breaker, an operating member connected to the breaker biased to an open circuit position and movable to a closed circuit position, a power spring, means for flexing said spring to store energy therein, means for releasably holding said spring in flexed position, a clutch mechanism interposed between said spring and said member operable to effect a driving connection therebetween, means for releasing said holding means and simultaneously operating said clutch mechanism to cause said spring to close the breaker, means for releasably holding said operating member in the closed circuit position comprising a stationary drum, a helical band rotatably disposed around said drum having its high torque end connected to the operating member, latch means for engaging and releasably holding the low torque end of said band when the operating member is in the closed circuit position whereby the bias of the operating member in said position causes said band to tighten and frictionally grip said drum, and means for releasing said latch means to allow said breaker to open.

18. In a control apparatus for a circuit breaker, an operating member connected to the breaker movable to open or close the same, a plurality of spiral power springs, means for flexing said springs to store energy therein, means for releasably holding said springs in flexed position, means including a band friction clutch mechanism interposed between said springs and

said operating member operable to effect a driving connection therebetween, an electromagnet for releasing said spring holding means, a second electromagnet for operating said clutch mechanism, and means for simultaneously energizing said electromagnets to cause said springs to move said operating member to close the breaker.

19. In a control apparatus for a circuit breaker, an operating member connected to the circuit breaker biased to an open circuit position and movable to a closed circuit position to open or to close the breaker, a plurality of spiral power springs having their inner ends secured to a stationary shaft and their outer ends secured to a bail rotatably mounted on said shaft, means for rotating said bail to flex said springs, means for releasably holding said bail in position with said springs flexed, a drum secured to said bail for rotation therewith, a helical band rotatably disposed around said drum having its high torque end connected to said operating member, an electromagnetic clutch interposed between the low torque end of said band and the drum operable to effect a driving connection therebetween, means for releasing said bail and simultaneously energizing said clutch to cause said springs to move said operating member to close the breaker, latch means for holding the operating member in the closed circuit position.

20. In a control apparatus for a circuit breaker, an operating member connected to the circuit breaker biased to an open circuit position and movable to a closed circuit position to open or close the breaker, a plurality of spiral power springs having their inner ends secured to a stationary shaft and their outer ends secured to a bail rotatably mounted on said shaft, means for rotating said bail to flex said springs, means for releasably holding said bail in position with said springs flexed, a drum secured to said bail for rotation therewith, a helical band rotatably disposed around said drum having its high torque end connected to said operating member, an electromagnetic clutch interposed between the low torque end of said band and the drum operable to effect a driving connection therebetween, means for releasing said bail and simultaneously energizing said clutch to cause said springs to move said operating member to close the breaker, a band friction light load latch means for holding the operating member in the closed circuit position, and a trip device for releasing said latch means.

21. In a control apparatus for a circuit breaker, an operating member connected to the breaker, biased to an open circuit position and movable to a closed circuit position to open or close the breaker, power spring means, motor means for flexing said spring means to store energy therein, latch means for releasably holding said spring means in flexed position, said motor means being automatically operable in response to release of said spring means to reflex said spring means to restore energy therein, means including a trip-free clutch mechanism interposed between said spring means and said operating member and an electromagnet for operating the clutch to effect a driving connection between said spring means and said operating member, an electromagnet for releasing said latch means, means for simultaneously energizing said electromagnets to cause said spring to move said operating member to close the breaker, a second latch means for releasably holding said operat-

ing member in the closed circuit position, and a trip device for releasing said second latch means.

22. In a control apparatus for a circuit breaker, an operating member connected to the breaker movable to open or close the same, a spiral power spring, means for flexing said spring to store energy therein, means for releasably holding said spring in flexed position, means including a band friction clutch and an electromagnetic clutch disposed in series relation between said spring and said member to effect a driving connection therebetween, and means for simultaneously releasing said spring holding means and energizing said electromagnetic clutch to cause said spring to drive said operating member to close said breaker.

23. In combination, a circuit breaker having an operating member biased to open circuit position and movable to closed circuit position, means for releasably holding said member in closed circuit position operable in response to predetermined conditions to release said member, reclosing means operable to halt opening movement of said operating member following interruption of the circuit and before said member reaches full open circuit position and to immediately return said member to closed circuit position, said last-mentioned means comprising a releasable power spring and means including a clutch for establishing a driving connection between the spring and said operating member to cause the spring when released to move the operating member to closed circuit position.

24. The combination with a circuit breaker having an operating member movable to open and to closed circuit position to open and to close the circuit, of a control apparatus for said breaker comprising an energy storing driving device for effecting closing of the breaker, said energy storing driving device constituting the only power device for closing said circuit breaker, means for storing energy in said device at a time prior to effective a driving connection of said device to said operating member, means operable to establish a driving connection between said device and said member and to cause said device to move said member to closed circuit position, said last-mentioned means being operable during an opening operation of the breaker to effect said driving connection and cause said device to initiate movement of said operating member to closed circuit position before said operating member reaches its full open position.

25. The combination with a circuit breaker having an operating member movable to open and to closed circuit position to open and to close the circuit, of a control apparatus for said breaker comprising an energy storing driving device, means including a motor for storing energy in said device, said energy storing driving device constituting the only power device for closing said circuit breaker, means operable to establish a driving connection between said device and said member and to cause said device to move said member to closed circuit position, said means being operable during an opening operation of the breaker to effect said driving connection and cause said device to initiate movement of said operating member to closed circuit position before said operating member reaches its full open position, and a trip means operable to release said driving connection and to cause

movement of said operating member to open circuit position.

26. The combination with a circuit breaker having a movable operating member biased to an open circuit position and movable to a closed circuit position, of a control apparatus for said breaker comprising an energy storing driving device for effecting closing of the breaker, said energy storing driving device constituting the only power device for closing said circuit breaker, means for storing driving energy in said device prior to effecting a driving connection of said device to said operating member, means operable to establish a driving connection between said device and said operating member and to cause said device to move said operating member to closed circuit position, said last mentioned means being operable at a predetermined point in the opening movement of said member to halt opening movement of said member before said member reaches full open position and return the same to closed circuit position, and trip means operable to disestablish said driving connection and to cause movement of said operating member to open circuit position.

27. The combination with a circuit breaker having an operating member movable to open and to closed circuit position to open and to close the circuit, of a control apparatus for said breaker comprising a single power closing device, said power closing device being the only power device for closing said circuit breaker, a disengageable clutch operable to establish a driving connection between said device and said member and means operable to operate said clutch and cause said device to move said member to closed circuit position, said means being operable during an opening operation of the breaker to establish said driving connection and cause said device to initiate movement of said operating member to closed circuit position before said operating member reaches its full open position, and a trip means operable to release said driving connection to cause said operating member to be moved to open circuit position irrespective of the position of said power closing device.

28. A high speed circuit breaker reclosing system comprising a circuit breaker having relatively movable contact structure, a single power motive device for actuating said contact structure to closed circuit position, said power motive device constituting the only power device for actuating said contact structure to closed circuit position, means actuated independently of the operation of said power motive device for tripping and causing opening movement of said circuit breaker, and means operated subsequent to said tripping means and prior to the completion of the opening stroke of said circuit breaker to initiate operation of said power motive device to reclose said circuit breaker within a fraction of the time required for a full stroke opening and reclosing operation.

29. A circuit breaker having relatively movable contact structure, actuating means comprising a single power motive device for actuating said contact structure toward closed circuit position, said power motive device constituting the only power device for closing said circuit breaker, control circuit means having contacts operative when closed to initiate closing operation of said power motive device, a latch for releasably holding said circuit breaker in closed circuit position independently of said power motive device, tripping means operable to release said latch to thereby cause opening of said circuit breaker contact structure, means operated subsequent to completion of the opening stroke of said circuit breaker to cause closing of said contact structure and thereby initiate operation of said power motive device to reclose said circuit breaker.

30. A circuit breaker having relatively movable contact structure, actuating means comprising a single power motive device for actuating said contact structure toward closed circuit position, said power motive device constituting the only power device for closing said circuit breaker, control circuit means having contacts operative when closed to initiate closing operation of said power motive device, a latch for releasably holding said circuit breaker in closed circuit position independently of said power motive device, tripping means operable to release said latch to thereby cause opening of said circuit breaker contact structure, means operated subsequent to completion of the opening stroke of said circuit breaker to cause closing of said contact structure and thereby initiate operation of said power motive device to reclose said circuit breaker within a fraction of the time required for a full stroke opening and reclosing operation.

31. A high speed circuit breaker reclosing system comprising a circuit breaker having relatively movable contact structure, a single power motive device for actuating said contact structure toward closed circuit position, said power motive device constituting the only power device for closing said circuit breaker, trip free structure for operatively relating said power motive device to said circuit breaker contact structure and providing means whereby said contact structure can be tripped free of said power motive device, a latch for holding said contact structure in closed circuit position independently of said power motive device, tripping means operable to release said latch to thereby cause opening of said circuit breaker contact structure, and means operated subsequent to completion of the opening stroke of said circuit breaker to cause closing of said contact structure and thereby initiate operation of said power motive device to reclose said contact structure within a fraction of the time required for a full stroke opening and reclosing operation, and means operable to cause opening of said contact structure irrespective of the condition of said control circuit means and the position of said control contacts.

32. A high speed circuit breaker reclosing system comprising a circuit breaker having relatively movable contact structure, a single power motive device for actuating said contact structure toward closed circuit position, said power motive device constituting the only power device for closing said circuit breaker, trip free structure for operatively relating said power motive device to said circuit breaker contact structure and providing means whereby said contact structure can be tripped free of said power motive device, a latch for holding said contact structure in closed circuit position independently of said power motive device, tripping means operable to release said latch to thereby cause opening of said circuit breaker contact structure, and means operated subsequent to completion of the opening stroke of said circuit breaker to initiate operation of said power motive device to reclose said circuit breaker contact structure within a fraction of the time required for full stroke opening and reclosing cycle.

33. A high speed circuit breaker reclosing system comprising a circuit breaker having relatively movable contact structure, a single power motive device for actuating said contact structure toward closed circuit position, said power motive device constituting the only power device for closing said circuit breaker, trip free structure for operatively relating said power motive device to said circuit breaker contact structure and providing means whereby said contact structure can be tripped free of said power motive device, holding means for holding said contact structure in closed circuit position independently of said power motive device, tripping means operable to release said holding means to thereby cause opening of said circuit breaker contact structure, and means operated subsequent to completion of the opening stroke of said circuit breaker to cause said

power device to initiate reclosing movement of said contact structure at an intermediate point in the opening stroke before said contact structure reaches full open position.

33. In combination, a circuit breaker having relatively movable contact structure, operating means therefor comprising a single power motive device for closing said circuit breaker, said power motive device being the only power device for actuating said circuit breaker to closed circuit position, control circuit means including control contacts operable when closed to initiate closing operation of said power motive device, a latch for releasably holding said circuit breaker contact structure in closed circuit position independently of said power motive device, tripping means operable to release said latch and thereby cause opening of said circuit breaker contact structure, means operated subsequent to said tripping means and prior to completion of the opening stroke of said circuit breaker to cause closing of said control contacts and thereby initiate operation of said power motive device to reclose said circuit breaker contact structure within a fraction of the time required for a full stroke opening and reclosing cycle, and means operable in response to predetermined conditions to cause opening of said contact structure to full open position irrespective of the position of said control contacts.

34. In combination, a circuit breaker having relatively movable contact structure, operating means therefor comprising a single power motive device for closing said circuit breaker, said power motive device being the only power device for actuating said circuit breaker to closed position, control circuit means including a closing relay energized in response to closing of an auxiliary switch interlocked with the breaker to close during the initial opening movement of said circuit breaker to at times initiate operation of said power motive device to automatically reclose said circuit breaker contact structure from an intermediate open position without allowing said contact structure to move to full open position, holding means for releasably holding said circuit breaker in closed circuit position independently of said power motive device, a trip device for releasing said holding means, and means operable in response to predetermined abnormal conditions to at times cause opening operation of said circuit breaker irrespective of the position of said closing relay.

35. In combination, a circuit breaker having relatively movable contact structure, operating means therefor comprising a single power motive device for closing said circuit breaker, said power motive device being the only power device for closing said circuit breaker, control circuit means energized in response to the closing of an auxiliary switch operated to closed position in response to the initial opening movement of said circuit breaker to at times initiate operation of said power motive device to instantly automatically reclose said contact structure from an intermediate open position without allowing said circuit breaker contact structure to move to full open position, and means operable upon the occurrence of predetermined abnormal conditions to at times cause opening operation of said circuit breaker irrespective of the condition of energization of said control circuit means and the position of said auxiliary switch.

36. A circuit breaker having relatively movable contact structure, operating means there-

for comprising a pivoted operating lever connected to the breaker and having a fixed stationary pivot that remains stationary during tripping and power closing and automatic reclosing of the breaker, a single power motive device operatively related to said lever for operating said lever to close the circuit breaker, said power motive device being the only power device for closing said circuit breaker, restraining device engageable with said lever to hold said breaker closed independently of the power motive device, a trip device for releasing said restraining means to thereby cause opening of said circuit breaker, control circuit means operable in response to the closing of an auxiliary switch operated to closed position during initial opening movement of the circuit breaker to at times initiate operation of said power motive device to reclose said circuit breaker contact structure within a fraction of the time required for a full stroke opening and reclosing operation, and means operable in response to predetermined abnormal condition in the main circuit upon reclosing of the breaker for instantly causing opening operation of the circuit breaker even though said power motive device has at the instant just reclosed said breaker or was operating at the instant to reclose the breaker.

37. A high speed operating mechanism for a circuit breaker comprising an operating member operatively related to the circuit breaker and movable to open and closed positions to open and close the circuit breaker, a single power motive device for actuating said operating member to closed position to close the circuit breaker, said power motive device being the only power device for actuating said operating member and circuit breaker to closed position, a latch for releasably holding said operating member in closed position to hold the circuit breaker closed independently of the power motive device, tripping means operable to release said latch to thereby cause opening movement of said circuit breaker operating member, means operated subsequent to said tripping means and prior to the completion of the opening stroke of said operating member to initiate operation of said power motive device to reclose said circuit breaker operating member within a fraction of the time required for a full stroke opening and reclosing cycle, and means operable in response to predetermined conditions to cause circuit breaker opening operation of said operating member irrespective of the closing movement and position of said power motive device.

38. A high speed reclosing mechanism for an electric circuit breaker comprising means for opening the breaker, a single power motive device comprising spring means for closing said circuit breaker, said spring means being the only power device for closing said circuit breaker, means for instantly releasing said spring means at a predetermined intermediate point in the opening stroke of said breaker for effecting high speed reclosure of said circuit breaker.

39. In combination, a circuit breaker biased to open circuit position, a single power motive device comprising a closing spring means for closing said breaker, said spring means being the only power device for actuating said circuit breaker to closed position, means for flexing said spring means to store energy therein and for releasably holding said spring in flexed position, means operable at a predetermined intermediate point in the opening stroke of said

breaker to release said spring means for instantly effecting quick reclosure of said circuit breaker, and means for releasing said circuit breaker from said spring means in response to predetermined abnormal conditions to allow said circuit breaker to trip open free of said spring means.

40. In combination, a circuit breaker, trip means operable to cause opening operation of said circuit breaker, a single power motive device comprising spring means for closing and reclosing said circuit breaker, said spring means being the only power device for actuating said

5 circuit breaker to closed circuit position, trip-free structure for operatively relating said spring means to said circuit breaker, means for at times releasing said spring means at a predetermined intermediate point in the opening stroke of said breaker to initiate quick reclosing operation of the breaker prior to completion of the opening stroke thereof, and means operable in response to predetermined abnormal conditions upon reclosing of the circuit for causing said trip-free structure to trip said circuit breaker free of said spring means.

JOSEPH W. OW.
